BASTING CLAMP

Louis A. Webb, Pasadena, Calif.

Application March 22, 1941, Serial No. 384,724

7 Claims. (Cl. 85—5)

This invention relates to basting tools for securing in assembled face-to-face relationship two or more plates of sheet metal or other material as a preliminary to performing an operation upon said plates requiring that they be firmly held in such assembled face-to-face relationship while the operation is being performed.

Basting tools of the class to which this invention relates find their most common field of use in securing and holding in fixed face-to-face relationship two plates previously drilled to provide a plurality of registering perforations for the reception of rivets, which, when installed in the perforations, permanently secure the plates together. After two such perforated plates are placed together with their registering perforations axially aligned several of the basting tools are placed in a corresponding number of registering pairs of perforations, rivets are installed in the remaining perforations, the basting tools are removed from the plates, and the perforations which had been occupied by the basting tools are then riveted.

It is one object of this invention to provide a basting tool which shall be simple, inexpensive of construction and positive and efficient in its action.

Another object of the invention is to provide a basting tool which may be speedily and readily applied and withdrawn from the plate to be riveted or otherwise operated upon.

It is another object of the invention to provide a basting tool of light weight and one which may be manually operated without the use of pliers or other auxiliary tools.

It is another object of the invention to provide a basting tool which may be inserted and withdrawn from the perforations in the plates with a rectilinear movement substantially perpendicular to the plates without the necessity of laterally shifting the tool during its movement into or out of the perforations.

While one embodiment of the invention is shown and described in the drawing and specification herein, the principles of construction which are characteristic of the invention are capable of embodiment in other similar tools, and while the particular embodiment shown and described herein is a tool intended primarily for use in preparing plates for being riveted together, it is apparent that this particular embodiment and other embodiments are capable of use for other purposes in other fields either for temporarily holding two objects in assembled relationship while work operations are being per-

formed upon them or for temporarily securing them together for other purposes or for effecting a permanent assembled relationship.

In the drawing, which is for illustrative purposes only:

Fig. 1 is a longitudinal sectional view of a basting tool embodying this invention and of two plates to be basted, the plunger of the tool being shown in fully projected position ready for passage through a pair of registering perforations in the plates;

Fig. 2 is a view similar to Fig. 1 with the tool in operative relationship to the plates and with the plunger partially retracted;

Fig. 3 is an enlarged top plan view of the tool shown in Figs. 1 and 2;

Fig. 4 is an enlarged longitudinal sectional view of the plunger shown in Figs. 1 and 2 taken along the line 4—4 of Fig. 1;

Fig. 5 is an enlarged transverse sectional view of the tool shown in Figs. 1 and 2 taken along the line 5—5 of Fig. 2;

Fig. 6 is a longitudinal sectional view of a modified form of the invention; and

Fig. 7 is a transverse sectional view of the tool shown in Fig. 6 taken along the line 7—7 of Fig. 6.

The tool comprises in general a body or housing 11, a plunger 12, and actuating and controlling devices for the plunger which will be named and explained in the course of the following description of the tool.

The body 11 comprises a metallic cylinder 13 open at each of its ends. Integrally secured to the upper end of the cylinder 13 are two diametrically opposite finger holds or handles 14 extending horizontally outwardly from the cylinder 13 and shaped in the form of a downwardly concave curve for comfortable conformation to the fingers of the operator. The upper terminal edges of the cylinder 13 between the handles 14 are bent horizontally inwardly to form two narrow lips 15.

A cylindrical cap 16 slidably fits within the upper end portion of the wall of the cylinder 13. This cap 16 has a side wall 17 and an upper end wall 18 providing a cylindrical recess 19. The outer surface of the wall 17 is formed with a downward facing annular shoulder 19a intermediate of its ends and an upwardly facing shoulder 20 near its lower end. As the cap 16 is reciprocally moved within the cylinder 13, the lips 15 serve as a stop to limit downward movement of the cap 16 upon engagement with the shoulder 19a and to limit upward movement of

the cap 16 upon engagement with the shoulder 20.

The plunger 12 is preferably made in the form of a cotter pin having an eye 21 at its upper end seated against the upper end wall 18 of the cap 16 and having a pair of legs 22 of substantially semi-circular cross sectional shape, and arranged, as in the usual cotter pin, in transverse alignment with each other, their flat faces 23 being in juxtaposed contact and the cross sectional shape of the two legs, when assembled, being substantially circular.

A cylindrical ring 24 snugly fits within the cylinder 13 near its lower end, and is held against longitudinal displacement with respect to the cylinder between a radially inwardly crimped annular bead 25 in the cylinder wall and a radially inwardly turned flange 26 formed on the lower end of the cylinder wall 13. The flange 26 is seated within an annular groove 27 formed in a gasket 28 of rubber or other deformable material. The gasket 28 prevents outward movement of the ring 24, and that portion of the gasket 28 which projects beyond the flange 27 engages, in a manner to be later explained, the inner face of the inner of two plates which are to be basted.

A helical spring 29 is operatively interposed between the eye 21 and the ring 24. This spring is under compression and applies a resilient pressure to the eye 21 and through it to the cap 16, causing the cap when otherwise free to move to assume a position in which the shoulder 20 engages the lip 19a and the plunger 12 is in a fully retracted position. The plunger 12 is moved against the action of the spring 29 from its fully retracted position to a fully projected position as shown in Figs. 1 and 4 when the operator places two of his fingers under the handles 14 and with his thumb presses down upon the end wall 18 of the cap 16.

The outer ends 30 of the legs 22 of the plunger 12 are pointed, and shaped so that when the legs are in transverse registry, as shown in Fig. 1, the two pointed ends form a cone-shaped tip which is readily insertable in a plate perforation. Just above the pointed end 30, each leg is recessed radially inwardly on one side to provide a shoulder 31, extending perpendicularly across the leg from the flat face 23. The end 30 is thus provided with a laterally extending lug 32. Spaced substantially inwardly from this shoulder and on the opposite edge of the flat face 23 of the leg a lug 33 is formed which projects outwardly from the leg in a direction parallel to the plane of cleavage between the flat faces 23 and opposite to the direction of lateral projection of the lug 32.

When the plunger 12 moves from its fully projected position shown in Fig. 1, inwardly, as it reaches a position relative to the housing, which is intermediate its position of full projection and full retraction, the lugs 32 engage an inner cylindrical face 34 of the ring 24, the lugs 32 acting as cam followers, and the cylindrical surface 34 acting as a cam to move the two legs 22 from a position of transverse alignment in parallelism with each other to a position in which they form a slight angle about the eye 21 as a center. This movement of the legs 22 is in planes parallel to the plane of cleavage between the flat faces 23 of the legs and is resiliently resisted by the torsional stress set up in a yoke portion 35 of the eye 21. When the legs 22 are thus spread, the lugs 33 move outwardly, as shown in Fig. 2. The distance longitudinally of the plunger between the 75

lugs 32 and the shoulder 31 at the juncture when the lugs 32 first engage the surface 34 is at least as great as the sum of the axial length of the ring 28 and the combined thickness of the plates 5 to be basted.

In using the tool, two plates 36 and 37 are placed together with their perforations, as, for instance, perforations 38 and 39, in registry. The tool is then grasped with two fingers placed under the handle 14 and the thumb placed on the top wall 18 of the cap 16, and the cap is depressed until the shoulder 19a engages the lip 15 and is held in that position against the compressive action of the spring 29. With the legs 15 22 in transverse registry and the outer ends 30 forming a conical point, the plunger is passed through the two perforations until the shoulders 31 are disposed beyond the outer face of the plate 37. Holding the plunger in this position with respect to the plates, preferably by pressing the lugs 32 against the inner face of the inner plate 36, the cylinder 13 is allowed to move downwardly by lightening the upward pressure under the handle 14. When the ring 24 in its downward movement engages the lugs 32, the legs 22 are angled sidewise with respect to each other enlarging the span of the end of the plunger in the plane of cleavage between the flat faces 23 of the legs of the plunger. As the upward pressure of the fingers under the handle 14 is further relaxed, the shoulders 31 are drawn upward into contact with the outer face of the outer plate 37 and the gasket 28 is forced downward against the inner surface of the inner plate 36, resiliently but firmly clamping the two plates together.

After the rivets have been installed in the perforations unoccupied by basting tools, each of the basting tools is withdrawn by grasping the tool between the fingers and thumb as before, projecting by thumb pressure the plunger to its outermost position in which the legs 22 of the plunger are again transversely aligned and, with the housing and plunger held in this relative position, withdrawing the plunger from the aligned perforations 38 and 39. This movement of withdrawal is facilitated if the shoulder 31 of each leg is shrouded by that portion of the other leg immediately opposite it as shown in Fig. 1. This shrouding is accomplished by properly shaping that portion of the leg lying between its lug 32 and its shoulder 31. The shrouding of each shoulder 31 by the portion of the other leg opposite the shoulder obviates accidental catching of either of the shoulders on the outer face of the outer plate as the plunger is being withdrawn.

It will be observed that the plunger is so shaped that it may be moved into and out of the perforation by a rectilinear movement in a path perpendicular to the plane of the plates. There are no projections on the housing and the plunger is smooth sided thus obviating the need of a transverse shifting of the plunger or an angling thereof during either the movement of insertion of the plunger through the apertures of the plates or a withdrawal of it therefrom.

If desired the caps 16 may be made of plastic material of different colors indicative respectively of the size of perforation for which the tool is adapted. Thus tools may be quickly selected from a pile containing tools of different colors, for any particular job in which the perforations are of a given size or sizes.

Fig. 6 and Fig. 7 illustrate another embodiment of the invention, representing a tool adapted for

use with thicker and heavier plates as in ship-building construction.

In this form of the invention the body or housing is a cylinder 41 formed with an inturned annular flange 42 at its upper end, and an inwardly enlarged wall 43 at its lower end. A winged nut 44 formed with an annular groove 45 is, in the process of manufacturing the tool, inserted in the open end of the cylinder 41 prior to the formation of the flange 42, and thereafter the flange is curled inwardly in seated relationship within the groove 45 permitting rotation of the nut 44 with respect to the cylinder 41. A plunger 46 has a threaded upper end 47 which engages the threads of a bore 48 of the nut 44. The lower end of the plunger 46 is split in the manner of a cotter pin providing legs 49 and 50. The upper portions 51 of the legs 49 and 50 are rectangular and slidably engage a correspondingly rectangularly apertured guide plate 52. The guide plate 52 is sprung into position during the course of manufacture and assembly of the tool with tongues 53 formed on the guide plate seated in conforming apertures 54 in the wall of the cylinder 41.

The legs 49 and 50 are provided with pointed ends 55, shoulders 56, and cam follower lugs 57 of the same character as the pointed ends 38, shoulders 31, and lugs 32 of the form of the invention shown in Figs. 1 to 5, inclusive. The lugs 57 cooperate with the inner face 58 of the enlarged wall 43 of the cylinder 41 in the same manner as do the lugs 32 with the inner face 34 of the ring 24.

The operation of the form of the invention shown in Figs. 5 and 6 is in general similar to that of the form of the invention shown in Figs. 1 to 5, inclusive. The differences in operation are obvious. The plunger is both projected and withdrawn by manually screwing the nut 44. No gasket corresponding to the gasket 28 is provided, because the type of work for which the tool is adapted, does not require protection of the inner face of the inner plate from being marred.

In the above description and in the claims the words "inner," "inward," and "inwardly" have been used to signify in a direction away from the plates to be basted, and the words "outer," "outward," and "outwardly" have been used in the opposite sense.

In the annexed claims the word "plunger" is used to denote a member, like the cotter pin 12, which is adapted to pass through the hole in the plates and engage the lower plate 31 by means similar to the shoulders or abutments 31, thus exerting an upward pressure on the lower surface of the lower plate. The plunger is divided into two "half plungers," the lower ends of which have a limited movement with relation to each other in a direction perpendicular to the surface of the paper, as shown in Fig. 4.

The body or housing 11 shown in Fig. 4 and the cylinder 41 shown in Fig. 6, with the parts rigidly attached thereto, are called "pressing members," since they press downwardly on the upper surface of the upper plate 36.

I claim as my invention:

1. In a tool for basting plates having registering perforations preliminary to installing permanent fastening devices in said perforations, the combination of: an elongated hollow housing open at each of its ends; a plunger in the form of a cotter pin longitudinally reciprocably mounted in said housing; an elongated closing cap longitudinally slidably mounted in one end of said housing and formed with a central in-

wardly opening bore recess, the eye of said cotter pin being seated against the bottom wall of said recess; stop means for limiting the movement of said cap in each direction; a centrally apertured ring concentrically fixed within the outer end of said housing, the shank of said cotter pin being loosely disposed within the aperture of said ring; a helical spring disposed under compression between said ring and said eye; oppositely disposed, inwardly facing shoulders formed on the outer ends respectively of the legs of said cotter pin, each of said shoulders being elongated in a direction perpendicular to and intersecting the cleavage plane between said legs; and oppositely disposed cam lugs on said legs of said cotter pin projecting from said legs in planes parallel to said cleavage plane, each lug being oppositely directed from its corresponding shoulder, said lugs being adapted to engage the wall of said central aperture of said ring and spread said legs, moving them in directions parallel to said cleavage plane against the spring action of said eye, and thereby spread said shoulders, as said cotter pin is retracted to a position in which said shoulders are spaced from the outer end of said housing a distance at least equal to the combined thickness of said plates.

2. In a basting clamp adapted to temporarily secure together two plates in desired alignment with each other prior to permanently securing said plates together, said clamp being adapted to be adjusted in a hole passing through both plates, and comprising: a plunger adapted to be inserted through said hole from an upper space adjacent the upper plate into a lower space adjacent the lower plate, said plunger being formed in two halves, the lower ends of the two half plungers having a limited movement with relation to each other in a direction parallel to a plane forming the dividing surface between said half plungers, each of said half plungers having an abutment formed near the lower end thereof and adapted to engage the lower surface of said lower plate adjacent said hole when said half plungers are moved into an expanded position; means for securing said half plungers together at their upper ends in such a manner that the lower ends of said half plungers are elastically forced into a retracted position so that they will pass readily through said hole; a pressing member surrounding said plunger and adapted to abut against the upper surface of said upper plate; cam means between each half plunger and said pressing member so placed that the lower ends of said half plungers are held in their expanded position with said abutments engaging the lower surfaces of said lower plate whenever said pressing member is forced into contact with the upper surface of said upper plate; and means acting between said pressing member and said plunger to pull said plunger upwardly and force said pressing member downwardly.

3. In a basting clamp adapted to temporarily secure together two plates in desired alignment with each other prior to permanently securing said plates together, said clamp being adapted to be adjusted in a hole passing through both plates, and comprising: a plunger adapted to be inserted through said hole from an upper space adjacent the upper plate into a lower space adjacent the lower plate, said plunger being formed in two halves, the lower ends of the two half plungers having a limited movement with relation to each other in a direction parallel

to a plane forming the dividing surface between said half plungers, each of said half plungers having an abutment formed near the lower end thereof and adapted to engage the lower surface of said lower plate adjacent said hole when said half plungers are moved into an expanded position; means for securing said half plungers together at their upper ends in such a manner that the lower ends of said half plungers are elastically forced into a retracted position so that they will pass readily through said hole; a pressing member surrounding said plunger and adapted to abut against the upper surface of said upper plate; cam means between each half plunger and said pressing member so placed that the lower ends of said half plungers are held in their expanded position with said abutments engaging the lower surfaces of said lower plate whenever said pressing member is forced into contact with the upper surface of said upper plate; and a compression spring surrounding said plunger and acting between said pressing member and said plunger to pull said plunger upwardly and force said pressing member downwardly.

4. In a basting clamp adapted to temporarily secure together two plates in desired alignment with each other prior to permanently securing said plates together, said clamp being adapted to be adjusted in a hole passing through both plates, and comprising: a plunger adapted to be inserted through said hole from an upper space adjacent the upper plate into a lower space adjacent the lower plate, said plunger being formed in two halves, the lower ends of the two half plungers having a limited movement with relation to each other in a direction parallel to a plane forming the dividing surface between said half plungers, each of said half plungers having an abutment formed near the lower end thereof and adapted to engage the lower surface of said lower plate adjacent said hole when said half plungers are moved into an expanded position; means for securing said half plungers together at their upper ends in such a manner that the lower ends of said half plungers are elastically forced into a retracted position so that they will pass readily through said hole; a pressing member surrounding said plunger and adapted to abut against the upper surface of said upper plate; a cam member formed on each of said half plungers on the side thereof opposite said abutment and so placed that they are engaged by said pressing member to force the lower ends of said half plungers into their expanded position when said pressing member is in abutment with the upper surface of said upper plate; and means acting between said pressing member and said plunger to pull said plunger upwardly and force said pressing member downwardly.

5. In a basting clamp adapted to temporarily secure together two plates in desired alignment with each other prior to permanently securing said plates together, said clamp being adapted to be adjusted in a hole passing through both plates, and comprising: a plunger adapted to be inserted through said hole from an upper space adjacent the upper plate into a lower space adjacent the lower plate, said plunger being formed in two halves, the lower ends of the two half plungers having a limited movement with relation to each other in a direction parallel to a plane forming the dividing surface between said half plungers, each of said half plungers hav-

ing an abutment formed near the lower end thereof and adapted to engage the lower surface of said lower plate adjacent said hole when said half plungers are moved into an expanded position; means for securing said half plungers together at their upper ends in such a manner that the lower ends of said half plungers are elastically forced into a retracted position so that they will pass readily through said hole; a pressing member surrounding said plunger and adapted to abut against the upper surface of said upper plate; a cam member formed on each of said half plungers on the side thereof opposite said abutment and so placed that they are engaged by said pressing member to force the lower ends of said half plungers into their expanded position when said pressing member is in abutment with the upper surface of said upper plate; and a compression spring surrounding said plunger and acting between said pressing member and said plunger to pull said plunger upwardly and force said pressing member downwardly.

6. In a basting clamp adapted to temporarily secure together two plates in desired alignment with each other prior to permanently securing said plates together, said clamp being adapted to be adjusted in a hole passing through both plates, and comprising: a plunger adapted to be inserted through said hole from an upper space adjacent the upper plate into a lower space adjacent the lower plate, said plunger being formed in two halves, the lower ends of the two half plungers having a limited movement with relation to each other in a direction parallel to a plane forming the dividing surface between said half plungers, each of said half plungers having an abutment formed near the lower end thereof and adapted to engage the lower surface of said lower plate adjacent said hole when said half plungers are moved into an expanded position; means for securing said half plungers together at their upper ends in such a manner that the lower ends of said half plungers are elastically forced into a retracted position so that they will pass readily through said hole; a pressing member surrounding said plunger and adapted to abut against the upper surface of said upper plate; cam means between each half plunger and said pressing member so placed that the lower ends of said half plungers are held in their expanded position with said abutments engaging the lower surfaces of said lower plate whenever said pressing member is forced into contact with the upper surface of said upper plate; a cap having a limited movement in the direction of the axis of said plunger in the said pressing member, the upper end of said plunger abutting in said cap; and a compression spring so placed that it forces said plunger upwardly and said pressing member downwardly.

7. In a basting clamp adapted to temporarily secure together two plates in desired alignment with each other prior to permanently securing said plates together, said clamp being adapted to be adjusted in a hole passing through both plates, and comprising: a plunger adapted to be inserted through said hole from an upper space adjacent the upper plate into a lower space adjacent the lower plate, said plunger being formed in two halves, the lower ends of the two half plungers having a limited movement with relation to each other in a direction parallel to a plane forming the dividing surface between said half plungers, each of said half plungers having an abutment formed near the lower end thereof and adapted

to engage the lower surface of said lower plate adjacent said hole when said half plungers are moved into an expanded position; means for securing said half plungers together at their upper ends in such a manner that the lower ends of said half plungers are elastically forced into a retracted position so that they will pass readily through said hole; a pressing member surrounding said plunger and adapted to abut against the upper surface of said upper plate; a cam member formed on each of said half plungers on the side thereof opposite said abutment and so

placed that they are engaged by said pressing member to force the lower ends of said half plungers into their expanded position when said pressing member is in abutment with the upper surface of said upper plate; a cap having a limited movement in the direction of the axis of said plunger in the said pressing member, the upper end of said plunger abutting in said cap; and a compression spring so placed that it forces said plunger upwardly and said pressing member downwardly.

LOUIS A. WEBB.
